UNITED STATES PATENT OFFICE

95,985

DESIGN FOR A BADGE

Alonzo R. Rowles, Washington, D. C.

Application February 12, 1935, Serial No. 55,377

Term of patent 3½ years

To all whom it may concern:

Be it known that I, Alonzo R. Rowles, a citizen of the United States, residing at Washington, District of Columbia, have invented a new, original, and ornamental Design for a Badge, of which the following is a specification, reference being had to the accompanying drawing, forming part thereof, in which

Fig. 1 is a front plan elevational view of the badge showing my new design; Fig. 2 is a side view thereof.

I claim:

The ornamental design for a badge, substantially as shown.

ALONZO R. ROWLES.
